PROCESS AND APPARATUS FOR COOKING THE DISCHARGED MATERIAL FROM LOW
TEMPERATURE DISTILLATION APPARATUS
Filed Dec. 22, 1921

UNITED STATES PATENT OFFICE.

EDWARD BARRS, OF LONDON, ENGLAND.

PROCESS AND APPARATUS FOR COOKING THE DISCHARGED MATERIAL FROM LOW-TEMPERATURE DISTILLATION APPARATUS.

Application filed December 22, 1921. Serial No. 524,155.

To all whom it may concern:

Be it known that I, EDWARD BARRS, a subject of the King of England, residing in London, England, have invented certain new and useful Improvements in a Process and Apparatus for Coking the Discharged Material from Low-Temperature Distillation Apparatus, of which the following is a specification.

10. This invention is for improvements in or relating to retorts or retorting-means for distilling or coking coal or both and has particular reference to the coking of coal discharged from a low temperature distillation apparatus.

According to this invention there is provided an apparatus for coking fuel and for the production of gas, a tubular retort in the form of a conduit through which fuel can be fed continuously, and one or more heating-jackets surrounding the conduit, in combination with one or more gas-withdrawing jackets that surround and open each through a plurality of ports into the interior of the conduit, which gas-withdrawing jackets preferably alternate with the heating-jackets.

When the apparatus as just described above is used with briquettes formed from material discharged from a low-temperature distillation apparatus, the said conduit may be of such a shape and size in cross-section that the briquettes fed through it make a sliding fit with and fill or substantially fill the cross-section of the conduit.

Conveniently, the parts of the coking apparatus set forth above are combined with a distillation-retort for partially distilling fuel, the material discharged from which is automatically fed to the tubular retort by way of a closed chamber.

In the accompanying drawings which illustrate diagrammatically one method of carrying out the invention—

45. Figure 1 is a central longitudinal section through the delivery-conduit at the point where coking occurs, the material being shown as fed through the conduit in the form of briquettes, and

50. Figure 2 is a general plan of the apparatus.

Like reference letters indicate like parts throughout the drawings.

Referring to the drawing, a tubular retort A in the form of a conduit is upwardly

inclined, as shown in Figure 1, either throughout the whole of its length or at one end, so that the briquettes may be fed in at the level of discharge from distillation apparatus and delivered at a point sufficiently elevated to fall into a wagon. In Figure 2 the distillation apparatus is indicated at B and may be similar in construction to that described in my concurrent United States patent specification Serial No. 523,456. 60

The distilled material is discharged automatically by any convenient means into a chamber B¹, whence it is fed by a conveyor into the briquetting apparatus C. This apparatus may be of any convenient construction wherein material to be briquetted is fed from a hopper and masses of it are rammed into a delivery-conduit, a separator being fed between each two adjacent masses during the ramming operation. In the drawing 70 a ram at the bottom of a hopper is shown at C¹, and the conduit A is that into which briquettes C² separated by separators C³ are rammed. At a convenient point along the conduit A two heating-jackets E are provided and two gas-receiving jackets F. The jackets are placed side by side, the heating-jackets alternating with the gas-receiving jackets. The conduit A is provided with 75 perforations A¹ at the points where it is surrounded by the gas-receiving jackets, and thus gas generated by the briquettes passing through the heated zones of the jackets E can be drawn off by the gas-receiving jackets F. 80

Conduits E¹ serve to circulate the heating medium (which may be any available hot fluid) through the jackets E, and conduits F¹ connect the gas-receiving jackets to permit the withdrawal of the gas therefrom. 85

It will be seen that this apparatus can be worked as a closed system, the coal being fed into the retort B by the hopper B², made to traverse the retort by mechanical means, such as are described in my earlier United States patent specification Serial No. 523,456 already referred to, discharged automatically into the chamber B¹ and raised thence by a conveyor to the hopper of the briquetting apparatus C. By this means it is delivered at the proper temperature into the briquetting apparatus and rammed into the delivery-conduit A so that it is formed into briquettes which are afterwards coked by passing through the areas surrounded by 105

the jackets E. Coal is thus fed in at one end of the apparatus and coke briquettes delivered from the other.

5 The conveyor, which may be disposed in the chamber B¹, constitutes no part per se of the present invention and therefore need not be described in detail.

10 In some cases it may be preferred to dispense with the briquetting apparatus and to feed the material in a loose form through the conduit A. It is of course not necessary to this invention that the material fed to the delivery-conduit A shall be delivered direct from the distillation retort, but this 15 is particularly advantageous where it is desired to form it into briquettes as it leaves the retort.

19 It will be appreciated that any number of heating-jackets and gas-withdrawing jackets 20 may be provided.

If it is desired to effect distillation by the 25 retort illustrated in Figure 1, it is only necessary to provide the gases or other heating-medium at the requisite temperature, say, 30 for low temperature distillation, and if coking is required subsequently a second series of heating and gas-collecting jackets could be arranged round the conduit at a further point along the same and supplied with a 35 heating-medium at a higher temperature. That is to say, the set of heating and gas-withdrawing jackets shown in Figure 1 may be duplicated, the heating medium supplied to the set through which the fuel first passes 40 being at a lower temperature than that of the heating medium supplied to the second set. Any number of heating-jackets and 45 gas-receiving jackets may be used and the conduit may be of any desired diameter, and when serving as a retort, say, for low temperature distillation, it could be arranged vertically, the coal being fed in at the top and controlled in its escape at the bottom so that it shall be held within the heated zone until the requisite degree of distillation has taken place.

What I claim as my invention and desire to secure by Letters Patent is:—

1. In apparatus for coking fuel and for 50 the production of gas, the combination with a tubular retort in the form of a conduit through which fuel can be fed continuously, at least one heating jacket surrounding a portion of said conduit, and means for supplying a heating medium to the heating jacket, of at least one gas-withdrawing jacket that surrounds another portion of said conduit, which latter portion has in its wall a plurality of ports that put the 55 gas-withdrawing jacket into open communication with the interior of said conduit, and means for conducting gas away from the gas-withdrawing jacket.

60 2. In apparatus for coking fuel and for the production of gas, the combination of

a tubular retort in the form of a conduit through which fuel can be fed continuously, and having imperforate and ported portions, a plurality of heating jackets surrounding each an imperforate portion of said conduit, means for supplying a heating medium to the heating jackets, a plurality of gas-withdrawing jackets surrounding each a ported portion of said conduit, which gas-withdrawing jackets alternate with the said heating jackets, and means for conducting gas away from the gas-withdrawing jackets.

3. In apparatus for coking fuel and for the production of gas, the combination of a 80 tubular retort having a ported and an imperforate portion and being in the form of a conduit through which fuel in the form of briquettes can be fed continuously which conduit is of such a shape and size 85 in cross-section that the said briquettes fed through it make a sliding fit with and substantially fill the cross-section of the conduit, at least one heating jacket surrounding an imperforate portion of said conduit, means for supplying a heating medium to the heating jacket, at least one gas-withdrawing jacket surrounding a ported portion of said conduit, and means for conducting gas away from the said gas-withdrawing jacket.

4. The combination of a tubular retort in the form of a conduit having ported and imperforate portions, briquetting apparatus for briquetting fuel and continuously feeding the briquettes through said conduit, each two adjacent briquettes being separated by a separator, which conduit is of such a shape and size in cross-section that the said briquettes fed through it make a sliding fit with and substantially fill the cross-section of the conduit, a plurality of heating jackets surrounding each an imperforated portion of said conduit, means for supplying a heating medium to the heating jackets, a plurality of gas-withdrawing jackets surrounding each a ported portion of said conduit, which gas-withdrawing jackets alternate with the said heating jackets, and means for conducting gas away from gas-withdrawing jackets.

5. A closed system coking-apparatus comprising the combination with a tubular coking retort in the form of a conduit having a ported and an imperforate portion, at least one heating jacket surrounding an imperforate portion of said conduit, means for supplying a heating medium to the heating jacket, at least one gas-withdrawing jacket surrounding a ported portion of said conduit, and means for conducting gas away from the gas-withdrawing jacket, of a low-temperature fuel-distillation retort for partially distilling fuel, a closed chamber connecting the latter retort with said coking

retort, and means for continuously feeding to said coking retort by way of said closed chamber the partially distilled fuel discharged from said low-temperature fuel-distillation retort.

6. A closed system coking-apparatus comprising the combination with a tubular coking retort in the form of a conduit having a ported and an imperforate portion, at 10 least one heating jacket surrounding an imperforate portion of said conduit, means for supplying a heating medium to the heating jacket, at least one gas-withdrawing jacket surrounding a ported portion of said conduit, and means for conducting gas away from the gas-withdrawing jacket, of a low-temperature fuel-distillation retort for partially distilling fuel, a closed chamber connecting the latter retort with said coking 20 retort, briquetting apparatus connected with said closed chamber and arranged to feed briquettes continuously through said coking retort, and conveyor means for feeding to said briquetting apparatus by way of said 25 closed chamber the partially distilled fuel discharged from said low-temperature fuel-distillation retort.

7. A closed system coking-apparatus comprising a tubular coking retort having ported and imperforate portions, a plurality of heating jackets surrounding each an imperforate portion of said retort, means for supplying a heating medium to the heating jackets, a plurality of gas-withdrawing jackets surrounding each a ported portion 30 of said retort, which gas-withdrawing jackets alternate with the said heating jackets, means for conducting gas away from the said gas-withdrawing jackets, a low-temperature fuel-distillation retort for 35 partially distilling fuel, a closed chamber connecting the latter retort with said coking retort, briquetting apparatus connected with said closed chamber and arranged to feed briquettes continuously through said 40 coking retort, and conveyor means for feeding to said briquetting apparatus by way of said closed chamber the partially distilled fuel discharged from said low-temperature fuel-distillation retort. 50

In testimony whereof I affix my signature.

EDWARD BARRS.
